UNITED STATES PATENT OFFICE.

ERNEST C. DYE, OF GREENVILLE, SOUTH CAROLINA.

TOOTH-BRUSH HOLDER, STERILIZER, AND DEHYDRATER.

1,181,862.

Specification of Letters Patent.

Patented May 2, 1916.

Application filed March 27, 1915. Serial No. 17,421.

To all whom it may concern:

Be it known that I, ERNEST C. DYE, a citizen of the United States, residing at Greenville, in the county of Greenville and State 5 of South Carolina, have invented new and useful Improvements in Tooth-Brush Holders, Sterilizers, and Dehydraters, of which the following is a specification.

My invention relates to tooth brush holders, and one of its objects is to provide a 10 holder and sterilizer whereby the brush may be sterilized, dried and protected securely against the access of dirt, moisture and disease germs.

15 A further object of the invention is to provide a brush holder which permits of the use of a volatile germicide in an effective manner, and which affords manifold conveniences and thorough sanitation in the use 20 and storage of the brush.

The invention consists of the features of construction, combination and arrangement of parts herein fully described and claimed, reference being had to the accompanying 25 drawings in which:

Figure 1 is a vertical longitudinal section of a holder embodying my invention. Fig. 2 is a sectional perspective view showing the parts of the closure cap separated and arranged in proper relationship. Fig. 3 is a vertical transverse section on line 3—3 of Fig. 1. Fig. 4 is a vertical transverse section on line 4—4 of Fig. 2. Fig. 5 is a bottom or lower end view of the brush receptacle. Fig. 35 6 is a view, partly in side elevation and partly in section, showing certain modifications.

In carrying my invention into practice, I provide a tubular or cylindrical receptacle 1, 40 of proper length and diameter to receive a tooth brush 2. This receptacle may be made of any desired or suitable material and has a closed lower end 3 and an open upper end 4, through which latter end the brush 2 is 45 inserted and removed.

The end 4 is adapted to be closed by a cap 5, which may be detachably fitted thereon in any preferred manner. As shown in Fig. 1, the cap 4 has a tight frictional engagement with the receptacle 1, and the upper closed end of said cap is provided with an apertured lug 6 by means of which the device as a whole may be suspended from a nail or other suitable support.

55 The end 3 of the receptacle 1 is provided with perforations 7, and the sides of said re-

ceptacle 1 are also provided with perforations 8 extending around said receptacle and from a point about midway of the length of said receptacle down to the lower end 3. 60 These perforations 7 are for the purpose of permitting the drainage off of any water or moisture which may be deposited in the receptacle from the brush, and both sets of openings 7 and 8 are also provided for the 65 purpose of permitting a circulation of air through the receptacle to dry out the brush after use, as will be readily understood. The cap 9 is provided to slip upon the perforated lower end of the receptacle 1 to normally 70 close the perforations 7 and 8, and this cap is preferably made of a greater length than the perforated portion and fitted so as to abut against a stop 10 just above the line of the perforations 8 when fully applied, so 75 that the lower closed end of the cap will depend below the perforated end 3 and form a chamber 11 to receive the drip water from the interior of the receptacle, thus insuring the complete removal of all moisture from 80 the interior of the brush containing chamber.

The cap 5 contains therein means for storing a volatile germicide and discharging the same in regulated quantities into the receptacle. As shown, the casing 12 projects 85 into the chamber of the cap from the outer closed end of said cap and contains a charge 13 of a suitable absorbent material, such as cotton, which is saturated with a volatile germicide, such as formaldehyde. This body 90 of absorbent material is retained in position by a flange retaining cap 14 threaded or otherwise in engagement with the casing 12 and having its body wall provided with perforations 15, through which perforations 95 suitable and regulated quantities of the liquid formaldehyde or vapor emanating therefrom may be allowed to pass into the receptacle 1 for the purpose of sterilizing 100 the brush and interior of said receptacle.

The perforations 15 are arranged in radial lines and are controlled by a valved disk or plate 15', pivoted, as at 16, to the said outer wall of the cap for a limited rotary movement, said plate being provided 105 with similar rows of perforations 17 and with a transverse strip or handle 18 projecting beyond diametrically opposite sides thereof, whereby the disk may be turned to throw the rows of apertures into and out 110 of registration or to bring them partially into register to control the supply of formal-

dehyd^ee to the receptacle or to entirely cut off such supply.

It will thus be understood that the receptacle contains a charge of a volatile germicide which may be supplied to the interior of the receptacle as desired and required, and the supply of which may be properly controlled. Also it will be evident that the vapor from this germicide descending into the receptacle will render the receptacle and brush absolutely sterile, and that an undue supply of the germicide to the interior of the receptacle may be at all times prevented, while the construction is such that upon the removal of the closure cap the interior of the germicide storage chamber may be conveniently reached to replenish the same whenever necessary. It will also be seen that after the brush is used and stored away, the moisture draining therefrom by gravity will pass downward into the chamber 11 of the cap 9, and that this cap may be adjusted or removed to expose some or all of the perforations 8 and 7 to permit air to circulate through the portion of the receptacle containing the brush head, by which the brush head will be quickly and thoroughly dehydrated or dried. The construction described also provides for the ready and convenient cleansing of the interior of the receptacle whenever a thorough washing or other cleansing is deemed necessary.

It will be understood that the lug 6 provides a ready and convenient means for suspending the brush from a nail or other suitable support in a bath room or from a toilet table or other support. As shown in Fig. 6, however, the lug 6 may be dispensed with and the receptacle may be provided with an annular rib or bead 18 for engagement with a spring clip 19 upon a support, whereby the device may be conveniently suspended or hung up.

In the form of my invention shown in Fig. 6, other modifications are also disclosed, the cap 5 being secured in position by means of separated spiral threads 20, while I have shown the perforations 8^a terminating above the lower end of the receptacle and the perforations 7 dispensed with, by which construction the cap 9 need only be

partly removed or revolved for the circulation of air and discharge of the water through the openings 8^a. This form of receptacle is designed more particularly for travelers' use, in guarding against any possibility of leakage. Also, as shown in Fig. 6, I may employ a chain or other flexible connection 21 between the receptacle 1 and 60 cap 9 in order to prevent possible loss of the latter.

I claim:

1. A device of the character described comprising a receptacle of a form and size 65 to receive a tooth brush, said receptacle being open at its upper end and having its lower portion provided with perforations in its sides, a removable cap for partially or wholly covering the perforated lower portion of said receptacle, a detachable cap for closing the upper open end of said receptacle, and means within said cap for holding and dispensing a volatile germicide.

2. A device of the character described 75 comprising a receptacle open at its upper end and having perforations in its sides at its lower end, a closure for the upper open end of the receptacle, and a cap for closing the perforated lower portion thereof, 80 said cap being of greater length than said portion so as to project below the lower end of the receptacle and form a moisture collecting chamber.

3. A device of the character described 85 comprising a tubular receptacle open at its upper end and having perforations in its bottom and also having perforations in its side from a point about midway of its length to its bottom, a closure for the upper open 90 end of the receptacle, and a cap for closing the lower end of the receptacle, said cap being of a length to inclose the perforated lower portion of the receptacle and to project below the perforated bottom thereof 95 and form a depending chamber below the said perforated bottom.

In testimony whereof I affix my signature in presence of two witnesses.

ERNEST C. DYE.
